Primary Examiner — Mimosa De*(74) Attorney, Agent, or Firm* — Antonio Papageorgiou; Meister Seelig & Fein LLP(57) **CLAIM**

The ornamental design for an articulating hunters backrest, as shown and described.

DESCRIPTION

FIG. 1 is a perspective view of one side and the front of the articulating hunters backrest according to one embodiment of my new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom view thereof; and,

FIG. 8 is a perspective view like FIG. 1, with the invention in an articulated position.

The dashed lines shown in the drawings illustrate environmental subject matter and form no part of the claimed design.
